(54) **COMPOSITION, FOR MEDICAL PURPOSES**

(76) Inventor: **Robert S. Bernard**

Robert J. Bernard.

The schedule referred to in these letters Patent and making part of the same containing a description in the words of the said Robert J. Bernard himself of his improvement in a compound or composition of matter for Medical purposes called a remedy for the Cholera.

To all to whom these presents shall come
Be it known that I Robert J. Bernard of Norfolk in the
county of Norfolk and State of Virginia have invented a new
and useful improvement in a composition of matter, for
Medical purposes "called remedy for Asiatic Cholera, Cholera
aerobus, Diarrhoea &c and that the following is a full and
exact description of the process, or proportion of compounding
the same viz. according to the proportions given of the following
ingredients. Sulphate of Alum. 2 grains. Syp. Cast. potass 1 drachm
Alcohol at 80 degrees above proof 40 drachms. Gum camphor
20 grains. Hoffmann's Sudsyne Elixer $\frac{1}{2}$ oz. White sugar $\frac{1}{2}$
oz. compound Tinct. Opium $\frac{1}{2}$ oz. Spirits Lavender 1 oz. pure
water 3 oz. which are to be mixed together and taken according
to the following directions viz. Take a table spoon full of the mix-
ture with the same quantity of water, every hour or half hour
as occasion may require, until vomiting, purging, and pains
have ceased. This Medicine has been administered to Children
affected with Diarrhoea or Cholera aerobus, in doses of a tea
spoon full with the same quantity of water, with complete success.
The bottle should be kept well corked. For testimony that the
above is a full and exact description of the composition of
matter, or the ingredients of which my Medicine is formed,
I have hereunto set my hand this thirtieth day of July
Eighteen hundred and thirty five.

Witnessed

Robert J. Bernard
